TALKING MACHINE.

1,412,059.

Specification of Letters Patent. Patented Apr. 11, 1922.

Original application filed July 2, 1915, Serial No. 37,731. Divided and this application filed July 6, 1917. Serial No. 178,973.

To all whom it may concern:

Be it known that we, MERVIN E. LYLE, JOHN J. SCULLY, and FRANK L. CAPPS, citizens of the United States of America, and 5 residents of Bridgeport, Connecticut, have invented a new and useful Improvement in Talking Machines, which invention is fully set forth in the following specification.

This invention relates to talking machines, 10 and it has for its object to provide a tone-arm and mounting therefor that are simple in construction, inexpensive to manufacture, easy to assemble, and efficient in operation, this application being a division of our application Serial No. 37,731, filed July 2, 1915, 15 entitled "Talking machines," patented February 4, 1919, Number 1,293,489.

The inventive idea is capable of receiving a variety of mechanical expressions, one of 20 which, for the purpose of illustrating the invention, is shown on the accompanying drawing, but it is to be expressly understood that such drawing is for the purpose of illustration only and not for the purpose of defining the limits of the invention, reference being had to the appended claims for 25 that purpose.

In said drawing:—

Fig. 1 is a perspective view of a talking 30 machine embodying one form of the invention;

Fig. 2 is a vertical sectional view through the tone-arm support.

Referring to the drawing, in which like 35 reference numerals indicate corresponding parts in both views, 1 designates a talking machine cabinet of any suitable construction, being shown as of that type wherein an amplifier 2 is enclosed within the same. 40 Also mounted within the casing 1 is any suitable form of motor (not shown), the motor being provided with the usual winding crank 3. 4 designates the usual turn-table, 5 a record-tablet, and 6 is a sound-box of any suitable construction.

Over an aperture suitably positioned in the top plate 7 of casing 1, and shown as situated in one corner thereof, is a tone-arm support 8 provided with two oppositely disposed horizontal slots 9, within which rest the ends of a horizontal pin 10 passing through the spherical enlargement 11 on the tone-arm 12, said tone-arm at its other

end supporting the aforesaid sound-box 6. The spherical enlargement 11 fits closely 55 within the upper portion of the support 8 but with sufficient clearance so as to permit the tone-arm to turn freely therein about vertical and horizontal axes. This construction enables the tone-arm to have universal 60 movement upon its bearing without providing any opening flaring outwardly from the interior of the sound conduit.

Within the tone-arm support 8 and beneath the spherical enlargement 11 of the 65 tone-arm is mounted a stirrup 13, which stirrup is connected to the wall of the tone-arm support on one side, at 14, at a point higher up, that is, in a higher horizontal plane, than is the other side 15 of the stirrup, and a coiled spring 16 is connected at its lower end to the bottom of said stirrup and at its upper end to the pin 10, in the axis of support 8. The higher end 14 of 70 said stirrup is in a position to be engaged by the lower edge of the spherical portion of the tone-arm when the latter is swung to one side of the record and the sound-box end thereof released, thereby limiting the 75 downward tilting or rocking action of the 80 tone-arm and acting as a support or stop to hold the tone-arm in an approximately horizontal position. On the other hand, the lower portion 15 of the stirrup is in a position where it will not be engaged by the 85 lower edge of the spherical portion of the tone-arm when the tone-arm is considerably elevated. At the same time, the point where the spring 16 is connected with the stirrup is sufficiently removed from the point where 90 said spring is connected to the pin 10 to afford the necessary yielding action and yet enable the spring to hold the parts in normal position and prevent play or rattle between said parts. Thus a single piece of 95 bent wire is caused to operate not only as a tone-arm stop but also as an abutment for the spring 16.

It will be observed therefore, that this invention provides an extremely simple, 100 cheaply manufactured tone-arm and support therefor, while providing efficiently for all of the movements incident to the perfect operation of the tone arm. Furthermore, while the invention has been illustrated as 105 embodied in that form of talking machine

wherein the sound amplifier is enclosed within a casing below the plane of the record-supporting turn-table, it is to be expressly understood that, by inversion and obvious modification of parts, the tone-arm mounting is capable of use in that type of talking machine wherein the sound amplifier is disposed in a plane above that of the turntable.

5 Various changes and modifications may be employed without departing from the spirit of the invention as defined in the appended claims. It will be apparent to those skilled in the art that all such changes and modifications are designed to be covered by said 10 claims.

What is claimed is:—

1. In a talking machine, the combination of a vertical tubular tone-arm support having oppositely disposed horizontal slots in 20 its walls, a tone-arm having a spherical end portion fitting in said support, a pin passing through said spherical portion with its ends resting in said slots, a stirrup in said tone-arm support, one end of said stirrup acting 25 as a stop to limit the downward tilting movement of the tone-arm, and a spring connecting the bottom of said stirrup and said pin.

2. In a talking machine, the combination of a vertical tubular tone-arm support, a 30 tone-arm mounted to turn on horizontal pivot means engaging openings in the sides of said support, and a rod extending across the interior of said support and acting as a tone-arm stop, one end of the rod being 35 higher than the other.

3. In a talking machine, the combination of a vertical tubular tone-arm support, a tone-arm mounted to turn on a horizontal pin engaging openings in the sides of said 40 support, a rod extending across the interior of said support and acting as a tone-arm stop to limit its downward movement, and a spring connected to said pin and said rod.

4. In a talking machine, the combination of a vertical tubular tone-arm support, a tone-arm mounted to turn on a horizontal pin engaging openings in the sides of said support, a rod extending across the interior of said support and having a depending stirrup bend therein, one end of the rod acting 50 as a stop to limit the movement of the tone-arm, and a spring connected to said pin and to the depending stirrup part of the rod.

5. In a talking machine, the combination of a vertical tubular tone-arm support, a tone-arm mounted to turn on a horizontal pin engaging openings in the sides of said support, a rod extending across the interior of said support having one end higher than 60 the other and provided with a depending stirrup bend, the higher end of the rod acting as a stop to limit the movement of the tone-arm, and a spring connected to said pin and to the depending stirrup part of the rod.

6. In a talking machine, the combination

of a vertical tubular tone-arm support, a tone-arm having an end fitting in said support, one of said members being provided with diametrically opposed horizontal slots, horizontal means maintaining said members 70 in operative relation and engaged in said slots, and a rod extending across said support and acting as a stop to limit the downward tilting movement of the tone-arm.

7. In a talking machine, the combination 75 of a vertical tubular tone-arm support, a tone-arm having an end fitting in said support, one of said members being provided with diametrically opposed horizontal slots, a horizontal pin maintaining said members 80 in operative relation and engaged in said slots, a rod extending across said support and acting as a stop to limit the downward tilting movement of the tone-arm, and a spring connected to said pin and rod.

8. In a talking machine, the combination 85 of a vertical tubular tone-arm support, a tone-arm having an end fitting in said support, one of said members being provided with diametrically opposed horizontal slots, 90 a horizontal pin maintaining said members in operative relation and engaged in said slots, and a rod having one end higher than the other extending across said support, the higher end of said rod acting as a stop to 95 limit the downward tilting movement of the tone-arm and the rod and pin forming supports for a tension means.

9. In a talking machine, the combination 100 of a vertical tubular tone-arm support, a tone-arm having an end fitting in said support, one of said members being provided with diametrically opposed horizontal slots, 105 a horizontal pin maintaining said members in operative relation and engaged in said slots, a rod having one end higher than the other extending across said support, the higher end of said rod acting as a stop to limit the downward tilting movement of the tone-arm, and a spring connected to said pin 110 and rod.

10. In a talking machine, the combination 115 of a vertical tubular tone-arm support, a tone-arm having an end fitting in said support, one of said members being provided with diametrically opposed horizontal slots, horizontal pivot means maintaining said members in operative relation and engaged in 120 said slots, and a rod extending across said support and having its ends at different elevations, one end of said rod being positioned to act as a stop for said tone-arm.

11. In a talking machine, the combination 125 of a vertical tubular tone-arm support, a tone-arm having an end fitting in said support, one of said members being provided with diametrically opposed horizontal slots, a horizontal pin maintaining said members in operative relation and engaged in said slots, a rod extending across said support 130

- and having its ends at different elevations, one end of said rod being positioned to act as a stop for said tone-arm, and a spring connected to said pin and rod.
- 5 12. In a talking machine, the combination of a vertical tubular tone-arm support, a tone-arm having an end fitting in said support, one of said members being provided with diametrically opposed horizontal slots, 10 a horizontal pin maintaining said members in operative relation and engaged in said slots, a rod extending across said support and having a stirrup bend therein, one end of said rod acting as a stop for said tone-arm, and a spring connected to said pin and to the stirrup bend of said rod.
- 15 13. In a talking machine, the combination of a vertical tubular tone-arm support, a tone-arm having an end fitting in said support, one of said members being provided with diametrically opposed horizontal slots, 20 a horizontal pin maintaining said members in operative relation and engaged in said slots, and a spring connected to said pin and 25 extending axially from said tone-arm to a fixed abutment.
14. In a talking machine, the combination of a tubular tone-arm support provided with diametrically opposed circumferential slots, 30 a tone-arm having an end fitting in said support and provided with a transverse pin engaged in said slots, and a spring connected to said pin and extending axially from said tone-arm to a fixed abutment.
- 35 15. In a talking machine, the combination of a tubular tone-arm support, a tone-arm having an end fitting in said support, one of said members being provided with opposed circumferential slots, a pin maintaining said 40 members in operative relation and engaged in said slots, and a spring connected to said pin and extending to a fixed abutment opposed to said pin.
16. In a talking machine, the combination 45 of a vertical conduit, a tone-arm having a spherical end portion mounted therein, a stirrup in said support, one end of said stirrup acting as a stop to limit the downward tilting movement of the tone-arm, and a spring connecting the bottom of said stirrup and said end portion of the tone-arm.
17. In a talking machine, the combination of a vertical conduit, a tone-arm universally connected thereto, and an abutment within said conduit extending transversely across it and acting to limit movement of the tone-arm in both directions.
18. In a talking machine, the combination of a vertical conduit, a tone-arm terminally connected thereto for universal movement, 60 and a rod mounted in the conduit adjacent the terminal of the tone-arm, one end of said rod being nearer the terminal than the other, said rod adapted to limit the movement of the tone-arm in one direction to a 65 greater extent than in the other.
19. In a talking-machine, the combination of a vertical conduit, a tone-arm universally connected thereto, means in said conduit adapted to abut the tone-arm to 70 limit its movement in one direction about its horizontal axis of rotation, and to permit of greater movement of the tone-arm about said horizontal axis in the other direction.
20. In a talking-machine, the combination of a vertical conduit, a tone-arm universally connected thereto, means extending across said conduit and disposed at a greater height therein at one side than at the other, 80 whereby it abuts the tone-arm to limit its movement in one direction about its horizontal axis of rotation, to a greater extent than in the other direction.
21. A tone-arm mounting for phonographs, including a tone-arm a support for the tone-arm, the tone-arm being pivotally and rotatably mounted on the support, and resilient means attached to the support at its axis of rotation and anchoring said tone-arm at the intersection of its pivotal and rotatable axes.

In testimony whereof we have signed this specification.

MERVIN E. LYLE.
